UNITED STATES PATENT OFFICE.

TIMOTHY GINGRAS, OF BUFFALO, NEW YORK.

AXLE-WASHER.

SPECIFICATION forming part of Letters Patent No. 444,218, dated January 6, 1891.

Application filed August 8, 1890. Serial No. 361,437. (No model.)

To all whom it may concern:

Be it known that I, TIMOTHY GINGRAS, of Buffalo, in the county of Erie and State of New York, have invented certain new and useful Improvements on Axle-Washers; and I do hereby declare that the following description of my said invention, taken in connection with the accompanying sheet of drawings, forms a full, clear, and exact specification, which will enable others skilled in the art to which it appertains to make and use the same.

This invention has general reference to improvements in axle-washers; and it consists, essentially, in the novel and peculiar combination of parts and details of construction, as hereinafter first fully set forth and described, and then pointed out in the claims.

In the drawings already mentioned, which serve to illustrate my said invention more fully, Figure 1 is a plan of a blank from which my improved washers are made. Figs. 2, 3, and 4 are plans of the washers as formed from blanks having different serrations.

Like parts are designated by corresponding letters of reference in all the figures.

The object of this invention is the production of leather-axle washers, especially those used on large axles, in a cheaper and more efficient manner than has heretofore been accomplished.

Its object is, furthermore, to provide in such washers retaining-spaces, wherein the axle-grease or other lubricant may lodge, and in case of heating on account of insufficient lubrication may melt, and thereby furnish the necessary lubricant to prevent damages and accidents.

This class of axle-washers, which are of comparatively large diameter, and which have a wide bearing-surface, have heretofore been made exclusively from hides of leather cut by suitable means into the required annular form. In the cutting there is a loss of leather amounting to over forty per cent. of the stock, whereby a great loss is sustained and the cost of the article unnecessarily increased. To overcome these objections, I proceed to manufacture these axle-washers from strips of leather, substantially as shown in Fig. 1, of proper width and thickness, and then slit this strip into two pieces A B, respectively, by a zigzag

cut, as shown, thereby producing on one of the edges of said pieces A B serrations A' B', respectively. This cutting may be done by 55 a knife, a suitable cutter, or by a revolving cutter, the latter device being the most economical one. I then form these strips into rings, as shown in Figs. 2, 3, and 4, and finally unite the abutting ends, (or overlapping 60 joints,) if desired, by cementing or by inserting staples C C', as shown in Fig. 2, over the joint, though I do not wish to confine myself to the latter method, inasmuch as the strips A B already form marketable articles, which 65 may be cut to proper length, and then bent into annular form and inserted into the axle-box by the purchaser. The manufacture of such wide washers from plain parallel strips is next to an impossibility, owing to the rigidity of the material, while by serrating one 70 of the edges, as described, these strips may be readily bent into proper form.

By spacing the serrations far enough apart I produce in the washer a series of notches b, 75 which may be of any width, according to the angles of the serrations, and they may be so arranged that the opposite sides of these notches will meet, or nearly so, as shown in Fig. 4, said notches forming receivers for the 80 axle-grease, which being of a pasty consistency will be retained in said notches until heat shall more or less liquify the same, and thereby allow the grease to escape. If desired, apertures or recesses a' may be produced in the body of the washers for a like purpose.

It will be observed that in carrying out this invention I need not necessarily sever a strip into two portions A B, but may serrate a strip 90 of proper width on one of its edges, the exact shape of said serrations being immaterial and a modification thereof being shown in Fig. 3. Other designs of such serrations than those shown may be adopted without changing the 95 nature of my invention. It will be further observed that by varying the width of the strips A B washers of different width may be produced in an obvious manner.

Instead of bending the strips so that the 100 serrations b are in the opening of the washer, they may be so bent that they are on the periphery thereof, such a reversal of the order of arrangement being clearly within the scope

of my invention. So may I serrate both edges of the strips and then form them into annulæ, if desired.

Having thus fully described my invention, I claim as new and desire to have secured to me by Letters Patent of the United States—

1. In the manufacture of leather axle-washers, a washer-blank of proper width and thickness having on one or both of its longitudinal edges serrations, as described, whereby a wide blank may be readily formed into a washer without upsetting the material, as and for the object stated.
2. A leather axle-washer formed from a blank of proper width and thickness and having serrations in one of its longitudinal edges and the meeting ends united by a suitable fastening, as stated.

In testimony that I claim the foregoing as my invention I have hereto set my hand in the presence of two subscribing witnesses.

TIMOTHY GINGRAS.
